GRINDING MACHINE

James Martin, Ferndale, Mich., assignor to Michigan Tool Company, Detroit, Mich., a corporation of Delaware

Application December 15, 1945, Serial No. 635,267

6 Claims. (Cl. 51—123)

1

This invention relates to grinding machines. More particularly, it relates to a grinding machine readily adaptable for grinding the involute surfaces on flanks of teeth of gear-like machine elements such as master gears, shaper cutters, and the like, which may vary widely as to size and number of teeth.

As is well recognized, involute surfaces on flanks of gear-like machine elements must be precisely and accurately ground to shape after hardening. Difficulty arises, however, when it becomes necessary to grind such surfaces on machine elements which may vary widely in size or number of teeth, and as is generally the case, are few in quantity.

Production equipment can be adapted, but it is a time consuming operation involving unwarranted costs. Such equipment requires a different master gear or master roll for each different machine element. Essentially, it is at best only an attempt to do tool work with production equipment. The problem is further complicated by the fact that equipment thus used is lost for some, not inconsiderable, time to production.

Obviously, such practice is not satisfactory and it is, therefore, a primary object of the present invention to provide an adaptable and yet at the same time precise, automatic grinding machine capable of grinding involute surfaces on flanks of teeth of gear-like machine elements which may vary widely in size or in number of teeth and which machine requires no master gear or master roll.

It is a further object of the present invention to provide a construction by which involute surfaces on flanks of dissimilar gear-like machine elements may be ground automatically and which in no way depends upon the skill or ability of an operator to produce work of extreme accuracy.

Another object of the present invention is the provision of apparatus which may be easily and conveniently adapted to grinding involute surfaces on the flanks of dissimilar gear-like machine elements. To accomplish this, an adjustable sine bar is provided which may be quickly and easily adjusted to adapt a machine of my invention for grinding dissimilar gear-like machine elements.

Another object of the present invention is the provision of apparatus in which the workpiece is automatically moved as it engages a grinding wheel in such manner it progressively contacts the surface of said wheel along an involute path.

Still further, it is an object of the present invention to provide a construction sufficiently

simple in operation it may be controlled and adjusted by relatively unskilled labor.

Still further, the invention contemplates provision of apparatus which may be placed in battery formation about an operator to save valuable floor space.

Many other and further objects, advantages, and features of the present invention will become apparent from the description which follows, when considered in conjunction with the accompanying drawings, in which like numerals indicate like parts wherever shown, and wherein:

Figure 1 is a front elevational view of a grinding machine embodying the improvements of the present invention with the means for vertically adjusting the grinding wheel shown partly in section for clarity.

Figure 2 is a left side elevation of the grinding machine shown in Figure 1, partly sectioned to show the adjusting means of the grinding head.

Figure 3 is a cross-sectional view taken on line 3—3 of Figure 2 to more clearly illustrate various parts of the apparatus.

Figure 4 is a fragmentary, elevational view, substantially on line 4—4 of Figure 1 with various parts in section, to illustrate more fully and clearly the construction and arrangement of parts.

Figure 5 is a fragmentary, sectional elevation taken on line 5—5 of Figure 1, showing the grinding head.

Figure 6 is a sectional view on line 6—6 of Figure 1, showing a portion of the grinding wheel and apparatus for truing the same.

Figure 7 is a diagrammatic sketch of a fluid operated system which may be used with the construction disclosed by the present invention.

Figure 8 is a section taken on line 8—8 of Figure 4, showing the fluid responsive piston and cylinder for moving the workpiece, one connection of which is displaced 90 degrees for clarity.

Figure 9 is a fragmentary, elevational view taken in the direction of arrow 9, Figure 1, with covering omitted, showing the indexing mechanism.

Figure 10 is a view taken in the direction of arrow 10, Figure 9.

Figure 11 is an enlarged section taken substantially on line 11—11 of Figure 9.

According to the present invention, a construction is provided in which a workpiece is positioned by means of a work holder so the involute surfaces thereof may be engaged in proper sequence by a surface of a rotating grinding wheel, said surface being normal to the axis of rotation of said wheel.

The work holder provides for moving the work-piece as it engages the surface of the grinding wheel in such manner it progressively contacts said surface along an involute path. An automatically actuated index mechanism presents each tooth to the grinding wheel until the operation is complete, at which time the grinding machine automatically ceases operating until restarted by the operator.

Provision is made by means of the work holder for accommodating a helical workpiece with angularly disposed flanks and also for accommodating a workpiece having flanks of considerable length, that is to say a workpiece having a wide face.

The drawings disclose but a single embodiment of the grinding machine of my invention, which will hereinafter be described more fully. It will become obvious that many modifications thereof and departure therefrom may be made without departing from the spirit or scope of the invention as described and as claimed in the herein-after appended claims.

For a more detailed description of the invention, reference may be had to the drawings in which a base is generally indicated at 1. Such base may be formed from an integral, hollow casting with doors through which access is gained to certain, hereinafter described, portions of the apparatus housed interiorly of said base.

In order to accomplish the grinding of a work-piece, a grinding head generally indicated at 2 is mounted on an upwardly directed portion of said base by means of T-bolts 3 which engage T-slots 4, 5 of slide plate 6.

Such plate 6 is received by machined surface 7 and slideway 8 of base 1 for sliding movement thereon and provides for adjustment of the grinding head to bring the grinding wheel into contact with the workpiece and arcuate adjustment of said grinding head to angularly position the grinding wheel to the pressure angle of the teeth of the workpiece in a manner to be later described.

Said grinding head provides for a generally circular, abrasive grinding wheel 9 which has surface 10 normal to its axis of rotation. This grinding wheel is mounted on a spindle 11 for rotation therewith by means of collar 12, thrust washer 13, and nut 14 threadably engaging said collar at 15. This combination is secured to said spindle by nut 16 threadably engaging said collar and spindle at 17, 18, respectively.

Spindle 11 is journaled for rotation in bushing 19 and thrust bearings 20, 21 of annular sleeve 22. The annular sleeve 22 is received in hollow annular support 23 which extends downwardly from slideable mount 24. Bolt 25 secures said sleeve 22 to said support 23. A nut 26 is provided to threadably engage spindle 11 at 27 and presses against bearing 20 to prevent side play of the spindle. Cap 28 is secured to sleeve 22 by bolt 29 to prevent foreign matter from entering the thrust bearings.

Said grinding head provides for driving grinding wheel 9 by means of a suitable electric motor 30. Motor 30 is secured to mounting plate 31 of said grinding head at an outwardly projecting portion 32 thereof. T-bolts 33 engage T-slots 34, 35 in said projecting portion to rigidly secure said motor thereto.

This driving is accomplished by energizing motor 30 to drive motor shaft 36 and pulley 37. Pulley 37 drives a continuous belt 38 to drive pulley 39 keyed at 40 to spindle shaft 11, rotating the same. It will be obvious that pulleys 37 and 39 may be chosen of suitable ratios to give the

speed desired to the grinding wheel. It will be observed, too, that adjustment is provided to obtain proper belt tension by shifting the position of motor 30. This is easily accomplished upon loosening T-bolts 33, permitting them to slide in T-slots 34, 35. Said motor may then be relocated to give the desired tension in the belt, and the bolts tightened.

It is pointed out that the grinding wheel driving means is independent of other driving means and motor 30 is independently controlled by start and stop buttons 41, 42, respectively, which control the supply of electric current to said motor 30.

To accomplish the extreme accuracy required in a grinding operation of this nature, it is necessary to dress the grinding wheel at intervals. Therefore, a means for dressing the grinding wheel is also provided on the grinding head.

The dressing of grinding wheel 9 is accomplished by means of dresser 43 mounted on outwardly extending ear 44 of the mounting plate 31. This dresser is thus mounted at the longitudinal axis of spindle 11 and is normal thereto. Said dresser is provided with a diamond-pointed tool 45 (Figure 6) at the end of rack 46. Rack 46 engages threaded portion 47 of feed screw 48 which is rotatably mounted in a suitable bearing at 49. It will be observed that as feed screw 48 is rotated by means of handwheel 50, rack 46 will advance tool 45 toward the periphery of the grinding wheel.

As a further aid in the dressing operation, previously described, slideable mount 24, carrying spindle 11 with grinding wheel 9, may then be moved laterally inwardly toward tool 45.

This slideable mount depends by means of slideway 51 from outwardly projecting portion 32 of mounting plate 31 with said slideway 51 and machined surface 52 of projection 32 providing for the sliding of said mount.

The sliding movement by which grinding wheel 9 is laterally moved is accomplished by means of feed screw 53 journaled for rotation in a suitable downwardly directed bearing plate 54 secured to outwardly projecting portion 32 by screw 55. The threaded portion 56 of said feed screw engages lead nut 57 anchored to slideable mount 24 by screws 58. A handwheel 59 is integrally connected with the feed screw and it will be observed, as said handwheel is rotated, slideable mount 24 may be slidably moved as described.

When the dressing operation is complete, grinding wheel 9 is returned by means of handwheel 59 to operative position and diamond tool 45 is retracted by means of handwheel 50.

It is pointed out that adjustment of the grinding wheel by means of handwheel 59 is only for use in the dressing operation. It is not intended to be used to adjust the grinding wheel during the grinding operation.

As hereinbefore stated, slide plate 6 provides for adjusting the grinding head to bring the grinding wheel into contact with the workpiece and angularly positioning the grinding wheel at the pressure angle of the teeth of the workpiece.

This adjustment is accomplished by means of feed screw 60 journaled for rotation in suitable bearing 61 of a gear housing 62. Such housing 62 is rigidly anchored at the top of the upwardly directed portion of base 1. Feed screw 60 is threadably received by lead nut 63 anchored to slide plate 6 by bolts 64. A bevel gear 65 at the upper extremity of said feed screw meshes another bevel gear 66 on rotatable shaft 67. Said shaft 67 is journaled for rotation, perpendicular to feed

screw 60, in bearing portion 68 of the gear housing 62. A conveniently accessible handwheel 69 is provided to rotate shaft 67, and it is clear from the described construction that rotation thereof will serve to vertically shift said slide plate 6 and the grinding head thereon.

In order that the grinding wheel may be locked in position when this adjustment is accomplished, a lock nut 70 with handle 71 is provided. Such lock nut serves to positively anchor the slide plate, and thus the grinding wheel in adjusted position.

Arcuate adjustment of the grinding head to angularly position the grinding wheel at the pressure angle of the teeth on the workpiece is accomplished by means of the arcuately disposed T-slots 4, 5, in slide plate 6. Such slots permit grinding head 2 to be moved arcuately as T-bolts 3 are loosened to move slidably in said slots.

This movement of the grinding head is accurately controlled by feed screw 72 journaled for rotation in outwardly directed bearing 73, which is mounted on upwardly directed portion of base 1, for rotation perpendicular to that of the feed screw. This feed screw is threadably received by lead nut 74, which is mounted on mounting base 32 for rotation perpendicular to that of the feed screw. The feed screw includes an integrally connected handwheel 75, which when rotated, causes the bodily shifting of the grinding head to position grinding wheel 9 accurately at a predetermined pressure angle. The bodily shifting of the grinding head as the feed screw is rotated necessitates having bearing 73 and lead nut 74 rotatable, as it will be observed that the feed screw will move arcuately as lead nut 74 travels on said feed screw. Suitable graduations are provided at 76 and 77 to measure angular displacement of the grinding wheel, thus permitting extremely accurate control over the adjustment thereof.

It will be clear that after the grinding wheel is adjusted to a predetermined pressure angle in the described manner, T-bolts 3 may be tightened in T-slots 4, 5, to lock the grinding head and thus the grinding wheel rigidly and securely in position.

In order to support workpiece 18 during the grinding operation, a work holder, which is generally indicated at 79, is mounted on base 1 below grinding head 2. This work holder is an integrated unit which coordinates the function of its components to accomplish the grinding of gear-like machine elements in a manner to be herein-after described.

Broadly, the work holder comprises a compound carriage 80, upon which are mounted work head 81 and tailstock 82.

The compound carriage, generally indicated at 80, consists of a lower reciprocable table 83, a middle adjusting table 84, a swivel 85, and an upper reciprocable table 86.

The lower reciprocable table 83 is provided to accomplish reciprocation of the work holder parallel to the pitch line of a flank of a tooth of the workpiece or movement which may be resolved into such reciprocation when grinding gear-like machine elements having wide faces; that is to say, those having flanks of considerable length. Means are provided, however, to prevent this reciprocation if the workpiece has a narrow face. In this event, table 83 may be, if desired, used as a manually operated adjusting table for placing the workpiece in predetermined, longitudinal location with respect to the grinding wheel and locked thereat.

Such table is slidably mounted upon slideway

37 and machined surface 88 of base 1. In order to accomplish reciprocation thereof, suitable driving means are housed interiorly of base 1 to be driven by motor 89 mounted therein at 90. 5 This motor is controlled initially by a manually operable selector switch not shown. The supply of electric current to said switch is controlled by start and stop buttons 91, 92, respectively, which are provided for main drive motor 89 as will be 10 later described. Thus, after the selector switch is closed to supply electric current to said motor, this motor may be then controlled by means of said start, stop buttons.

Upon initiating operation of motor 89, said 15 motor drives motor shaft 94 and a clutch unit 95 keyed thereto at 96. This clutch unit is provided with jaws 97 to engage jaws 98 of a slideable clutch unit 99 mounted to slide upon shaft 100 which it drives by means of key 101. It is 20 pointed out that the clutch units are shown disengaged (Figure 3) for clarity. It will be obvious that said units must be engaged when reciprocation is to be accomplished by means of motor 89. Such shaft 100 is journaled for rotation in bearings 102, 103, provided by ribs 104, 105 of motor mount 99 in base 1. Longitudinal, axial movement of said shaft is prevented by means of thrust washers 106, 107, and thrust collars 108, 109 pinned thereto at 110, 111. Gear 112, integrally 25 connected to shaft 100 by means of key 113 and nut 114, is driven by said shaft. Gear 112 meshes gear 115, which gear 115 is integrally connected to shaft 116 by means of key 117 and nut 118 which threadably engages said shaft, and drives 30 the same. Shaft 116 is journaled for rotation in bearings 119, 120 of previously described ribs 104, 105 and is prevented from moving longitudinally by means of thrust washers 121, 122 and thrust collars 123, 124 pinned thereto at 125, 126. Said 35 shaft 116 drives gear 127 pinned thereto at 128, which gear meshes gear 129 keyed at 130 to drive feed screw 131 for driving table 83.

Such feed screw 131 is journaled for rotation 40 in bearing 132 provided by base 1, and bearing 133 anchored to project outwardly from said base. 45 This feed screw is threadably received by a lead nut 134 anchored to depend from table 83. It is clear from the description that table 83 will be shifted as the feed screw rotates to accomplish 50 the bodily shifting of the work holder.

Automatic reciprocation is provided by means 55 of limit switch 135 which reverses the rotation of motor 89. Dogs 136, 137, depending by means of T-bolts 138 from reciprocable table 83, are positioned to contact switch arm 139 of said switch. Such dogs may be shifted by slidably moving T-bolts 138 in T-slot 140 to terminally limit the travel of table 83 to the length of the tooth flank. As each dog reaches its respective limit, it contacts said switch arm 139 effecting reversal of 60 the rotation of motor 89, changing the direction of reciprocation of table 83.

It is to be observed that this reciprocation is 65 not always parallel to the pitch line of a flank of the workpiece. This reciprocation is along an axis of the grinding machine. When the workpiece has angularly disposed flanks, as is the case with a helical gear, this reciprocation is resolved into reciprocation parallel to the pitch line 70 of a flank tooth by means of swivel 85 in a manner to be explained as said swivel and its function are described.

Control over the speed of reciprocation is provided by means of change gears 112, 115. Said 75 gears become accessible upon removal of door 141.

covering opening 142 provided in base 1. The gears may then be replaced by others having a ratio suitable to produce the desired speed of reciprocation.

As previously stated, it is sometimes desirable to prevent reciprocation of table 83 and use it for adjustment only. In this event, the selector switch controlling motor 89 is left open and said motor is idle. When such is the case, the jaws of clutch units 95, 98 are disengaged to permit manual operation of the feed screw 131.

This is accomplished in the following manner. A spline shaft 143 is mounted for rotation in bearings 144, 145 provided by bosses projecting from the walls of base 1. Such shaft engages the annular teeth-like grooves of slidable clutch unit 98. It will be observed that rotation of shaft 143 will accomplish the slidable shifting of said unit upon shaft 100 and disengagement of said units will result if shaft 143 is rotated in a direction away from clutch unit 95. This will leave feed screw 131 and the driving means thereof free to be rotated by a conveniently accessible handwheel 146. Said handwheel may then be slidably moved inwardly on feed screw 131 to effect engagement of jaws 147, 148 of clutch units 149, 150, respectively. It will be clear that thus engaged, these units will cause rotation of the feed screw as the handwheel is manually turned, inasmuch as unit 149 is integrally connected to said handwheel and unit 150 is pinned at 151 to the feed screw 131. It will be observed that the shifting of table 83 will then be accomplished as the handwheel is turned in a manner similar to that previously described for reciprocation thereof.

In order that table 83 may be, when manually adjusted, locked in predetermined, adjusted position if desired, a lock nut 152 is provided. By means of handle 153 attached thereto, it is possible to tighten said nut and positively anchor said table in predetermined, adjusted longitudinal position with respect to the grinding wheel.

In order to position the workpiece laterally with respect to the grinding wheel, work holder 80 provides what I have chosen to call a middle adjusting table 84. This table is slidably mounted upon surface 154 and slideway 155 on top of table 83 to move in a direction perpendicular to the direction of reciprocation of said table 83. As in the case of table 83, swivel 85 must be used in conjunction with this table when the flank of a tooth of the workpiece, as for example a helical gear, is angularly disposed with respect to its axis of rotation in order to resolve the shifting movement into movement normal to the pitch line of the tooth flank. When, however, the workpiece is, for example, a spur gear or its equivalent, it is equally obvious that swivel 85 need not be used, inasmuch as the flank of a tooth on such type workpiece is not angularly disposed with respect to said axis. In this case, shifting of table 84 accomplishes the desired result directly.

This slidable shifting of table 84 to laterally position the work holder, and thus the workpiece, is accomplished by means of feed screw 156. Said feed screw is journaled for rotation in suitable bearings 157, 158 provided by gear housing 159 anchored to table 84, at one extremity thereof. Said feed screw threadably engages lead nut 160 anchored to depend from said table. A gear 161 is pinned at 162 to said feed screw to mesh gear 163 pinned at 164 to shaft 165.

This shaft 165 is rotatably supported by bearings 166, 167 of said gear box and has a handwheel 168. It will be clear from the description that rotation of the handwheel imparts rotation to the feed screw by means of the gears to shift the table for laterally adjusting the position of the work holder.

In order to lock the work holder in predetermined lateral adjustment, if desired, a lock nut 169 is provided. This lock nut may be tightened by means of handle 170 to positively and rigidly anchor table 84 in predetermined lateral adjustment with respect to the grinding wheel.

As stated herein previously, in connection with the description of tables 83 and 84, provision is made in the work holder to accommodate a workpiece, such as a helical gear, having the flanks of the teeth angularly disposed with respect to the axis of rotation. Adjustment for this condition is provided by means of swivel 85 of said work holder. Such swivel 85 is rotatably mounted upon machined surface 171 of table 84 by means of pivot pin 172 to rotate in a plane parallel to the axis of rotation of the workpiece.

Rotation thereof is accomplished as a worm 173 is rotated to travel on worm gear 174. Said worm is supported for rotation in suitable bearings (not shown) in a downwardly directed side of said swivel. Within the interior of said swivel 85, worm gear 174 is concentrically mounted with respect thereto by means of the pivot pin 172. Hub 175 of said gear is anchored to table 84 by bolt 176, preventing rotation thereof. This hub is of sufficient height to line up the gear with the worm. The pinion shaft 177 is provided with squared end 178 to which a crank or other suitable means may be applied to rotate said pinion. As said worm 173 is thus rotated, it moves swivel 85 around the stationary gear 174 by means of shoulder 179 on shaft 177 which bears upon the side of the swivel. In this manner, a flank of a tooth of the workpiece may be placed parallel to the plane of rotation of the grinding wheel.

It is this rotational adjustment which resolves the reciprocation of table 83 into reciprocation parallel to the pitch line of a flank of a tooth of the workpiece and resolves the lateral adjustment provided by table 84 into movement normal to said pitch line when said flank is angularly disposed with respect to the axis of rotation of the workpiece.

When this rotational adjustment is accomplished, swivel 85 may be locked in predetermined angular position by means of T-bolt 180 which moves slidably in the circular T-slot 181 provided by table 84. Swivel 85 has a depressed portion 182 in its downwardly directed side by which access may be obtained to a nut 183. Said nut 183 threadably engages T-bolt 180 and provides for tightening said bolt in T-slot 181 rigidly locking the swivel in adjusted position.

The angular setting of the swivel 85 is controlled with extreme accuracy by a finely graduated, circular index band 184 mounted on table 84 at the periphery of machined surface 171 (Figures 1 and 3). As said swivel is rotated, an index pointer thereon at 185 accurately indicates the angular position thereof by means of band 184.

With a grinding machine of my invention, the workpiece is reciprocated normal to its axis of rotation during the grinding operation. This reciprocation is provided by upper reciprocating

table 86. The work head 81 is integrally a part of table 86 and tailstock 82 is adjustably mounted thereon by means of T-bolt 186 mounted to slide in T-slot 187. Inasmuch as tailstock 82 is conventional and is not claimed as part of this invention, it is not further described.

Table 86 is mounted on balls 188 in raceways 189, 190, 191 to reciprocate upon swivel 85. It will be observed that this table, and hence the work head and tailstock are rotatable to angular position by means of the swivel.

Reciprocation of the workpiece by means of table 86 is effected as a slide block 192, operatively associated with a fluid responsive cylinder 193, reciprocating perpendicularly to the plane of reciprocation of said table, is propelled by such cylinder in such manner it is slidably moved along a sloping sine bar 194.

The sliding movement of the slide block 192, resulting in reciprocation of table 86, is brought about in the following manner. Work head 81, previously noted as being integral with reciprocating table 86, provides machined surface 195 and slideway 196 to slidably receive side 197 of reciprocating cylinder 193. At the upper extremity of said machined surface 195 and slideway 196, the work head provides an outwardly projecting arm having opening 198 therethrough through which piston rod 199 is permitted to extend. Such piston rod is rigidly secured therein by bolt 200 and held in its stationary position as said cylinder reciprocates. An outwardly directed projection of cylinder 193 forms ear 201 which provides a suitable opening through which pin 202 of slide block 192 is permitted to extend. Thus, as fluid is admitted at alternate intervals to chambers 203, 204 (Figure 8) on opposite sides, respectively, of piston 205 in said cylinder 193, such cylinder reciprocates, and it is evident that slide block 192 will tend to move with said cylinder. However, this slide block is constrained by groove 206 of sloping sine bar 194 and can only slide therein. It will be apparent that as slide block 192 slides in groove 206, it travels laterally with respect to the grinding wheel. It is this lateral movement of the slide block which shifts table 86 and workpiece 78 therewith.

In order to reciprocate table 86 automatically, pilot valve 207 is provided to effect the directing of pressurized fluid alternately to chambers 203, 204 of the cylinder 193. This valve 207 is provided with arms 208, 209 to be contacted by dogs 210, 211, mounted on said cylinder 193, as each in turn reaches its terminal limit. Upon contact, said valve arms 208, 209 cause the shifting of a piston (not shown) in a four-way valve 212 to direct the pressurized fluid to opposite sides of piston 205.

The grooved sine bar 194 controls the reciprocating movement of table 86. This sine bar is mounted on an outwardly extending arm of previously described table 85 for arcuate adjustment into a sloping position. T-bolts 213 slidable in arcuate T-slot 214, in said extending arm, provide means for rigidly locking the sine bar in predetermined sloping position. This slope may be accurately controlled by suitable means such as gage blocks which may be placed between polished surface 215 on said extending arm and measuring pin 216 on said sine bar. It will be observed that sine bar 194 must be angularly adjustable to the angular position of table 86 in order to maintain slide block 192 in groove 206. This was accomplished by mounting the sine bar on an extension of the swivel 85.

Control of the reciprocatory movement of table

86 by means of sine bar 194 is accomplished by changing the slope of the same. This desirable result is utilized to eliminate the necessity of using a master roll on a grinding machine of my invention. It is this simple expedient which permits a grinding machine of my invention to be easily and quickly adapted to grinding gear-like machine elements which vary widely in size and number of teeth.

During the grinding operation, workpiece 78 is rotatably supported between spindle 217 of work head 81 and center 218 of tailstock 82 by suitable means for rotation by said spindle.

For the purpose of grinding a flank on a tooth of the workpiece, said workpiece is partially rotated in an oscillatory manner about its axis of rotation. For indexing, the workpiece is intermittently rotated until all the teeth thereon have been presented to the grinding wheel. Work head 81 provides separate means by which this partial and intermittent rotation is separately imparted to said workpiece.

In order to provide for the partial and indexing rotation of workpiece 78, spindle 217 is journaled in compound bearings 219, 220, 221, provided by said work head 81, and a sleeve 222, for rotation within said sleeve. Such spindle 217 is held therein by nuts 223, 224 which threadably engage said spindle and prevent longitudinal axial movement thereof.

Various interconnected, mutually operable, units are provided by the work head 81 to accomplish the partial rotation of workpiece 78 by means of spindle 217.

Sleeve 222 in which spindle 217 rotates is journaled for independent rotation in compound bearings 225, 226 and upon the outer races of compound bearings 220, 221. This sleeve is integrally connected by bolt 227 to rotatable disc 228 and provides for rotatably supporting said disc.

Such disc 228 has flexible bands 229, 230 secured in grooves at the top center thereof by tabs 231, 232 and flexible band 233 secured in a groove at the bottom center thereof by tab 234. It is to be noted that the combined width of upper bands 229, 230 equals the width of lower band 233. In this way, the tension exerted by the bands on disc 228 is equalized. The opposite ends of said bands 229, 230 are secured to the bottom of reciprocating cylinder 193 by clip 235 and, thus connected, are partially wound on the periphery of disc 228. The opposite end of band 233 is secured to the top of said reciprocating cylinder 193 by tab 236 and this is partially wound on the periphery of disc 228 between bands 229, 230. In order to adjust the length of the bands, clip 235 provides for the same with an adjusting bolt at 237. By means of this adjustment, bands 229, 230 may be lengthened or shortened, automatically adjusting band 233. It will be clear from the description that as cylinder 193 reciprocates, the bands will cause disc 228 to rotate in an oscillatory manner as they alternately wind and unwind on disc 228.

This rotative movement is transferred to a worm gear 238 integrally connected to disc 228 and to a built-up support 239 anchored to face plate 240 of said gear. Support 239 carries therein a push pin 241, which pin has at its upper extremity a lip 242 in which a groove 243 is provided. Within this groove, an index finger 244 is held by pin 245 to extend downwardly parallel to the longitudinal axis of push pin 241. The front face of support 239 provides an elongated

11

gated opening 246 through which a pin 247, secured to index finger 244, is permitted to pass. This pin prevents sidewise movement of said index finger.

The index finger, thus held, is disposed between the peripheral serrations 248 of an index plate 249 integrally connected to an extremity of spindle 217 by means of nut 250. In this manner, the rotative movement of disc 228 is imparted to the index plate and thence to the spindle 217 and workpiece 78.

It is this partial rotation of the workpiece which combined with the reciprocatory movement provided to said workpiece by table 86 effects a flank of a tooth thereon to progressively contact the surface 10 of the grinding wheel along an involute path.

It is a fact, recognized by those skilled in the art, that a machine element, such as a gear, having involute teeth will roll in a rack having straight teeth. In a grinding machine of my invention this principle is utilized. The straight surface 10 of the grinding wheel can be considered one side of a tooth of an imaginary rack. The combined rotative and reciprocatory movements given the workpiece produce a resultant rolling movement effecting a flank of a tooth on said workpiece to roll into and out of engagement with said surface of the grinding wheel in a manner similar to that of a gear tooth on a reciprocating gear rolling into and out of engagement with a rack tooth. It is apparent that the linear movement, as measured at the axis of rotation of a gear thus rolled, is affected by the size of the gear or number of teeth thereon in order for a tooth thereof to roll out of engagement with the rack. In production equipment, a different master roll or master gear is provided for each different gear to properly move a workpiece thereon. A machine of my invention, as stated previously, requires neither a master roll nor master gear to supply the proper linear movement to the workpiece during the grinding operation. The previously described adjustable sine bar controls, with extreme accuracy, the reciprocation of table 86 to provide the required linear movement for any workpiece regardless of size or number of teeth thereon. It will be evident, too, that said sine bar may be readily and quickly adjusted by comparatively unskilled labor to adapt a grinding machine of my invention for grinding gear-like machine elements which vary widely in size and number of teeth. Thus, by utilizing a well-known principle, I have invented a new and novel method of providing the required linear movement to a workpiece whereby a single grinding machine may be easily adapted for grinding gear-like machine elements varying widely in size and number of teeth without using a master roll or master gear.

The indexing rotation provided by work head spindle 217 to present each tooth of the workpiece to the grinding wheel is accomplished after table 86, of which said work head is an integral part, is reciprocated a definite number of times by means of cylinder 193.

As said cylinder 193 reciprocates, lower runner 251, and upper runner 252 thereon slidably contact limit switches 253, 254, respectively. Upon contact, said switches complete electrical circuits to a counting device (not shown) for counting the number of reciprocations. This device may be adjusted to permit cylinder 193 and table 86 to reciprocate, in accordance with the

12

will of the operator, a predetermined number of times to permit the tooth being ground to acquire a fine finish.

When the desired number of reciprocations have been made, various mutually operative units effect indexing rotation of spindle 217 and thus, workpiece 78.

At this instant, the counting device closes another electrical circuit, energizing solenoid valve 255. This valve then permits pressurized fluid to enter chamber 256 of cylinder 257 anchored to the work head. As fluid enters this chamber, fluid responsive piston 258 and piston rod 259, to which rack 260 is integrally connected, reciprocate inwardly.

Such rack 260 is provided to simultaneously rotate gear 261 slidably mounted upon bushing 262 on sleeve 222, and to oscillate a shifter 263 for slidably moving said gear toward surface 264 of index plate 249. This movement of shifter 263 causes contact pins 265 thereon to press upon surface 266 of gear 261 for effecting sliding movement of said gear toward surface 264 of index plate 249. This sliding movement of gear 261 increases the pressure between friction buttons 267, carried by gear 261, and surface 264 of index plate 249 to accomplish rotation of said plate by means of said gear.

In order to oscillate shifter 263, rack 260 is thin at one extremity and sloped at 268 to a greater thickness. As said rack reciprocates inwardly, the head of a bolt 269, passing through the shank of shifter 263 to contact said rack, effects said shifter to move in an oscillatory manner about pin 270 because of this variation in thickness of rack 260. Such pin 270 extends through mating openings in said shifter shank and supports 271, 272 provided to slidably support rack 260 upon machined surfaces 273 thereof.

The friction buttons 267, by which gear 261 rotates index plate 249, are carried within blocked openings 274 of gear 261. Compression springs 275 are disposed within cavities 276 of said friction buttons and bear upon the lower surface of openings 274. A neck portion 277 of said friction button protrudes through a drilled opening in shoulder nut 278 which threadably engages a tapped portion of blocked opening 274. It will be observed that as said nut is tightened, it bears upon shoulder 279 of friction button 267, compressing spring 275 to yieldingly mount said friction button in said opening 274. Thus, as gear 261 slidably moves toward surface 264 of index plate 249, it will be evident that the pressure between said friction buttons 267 and surface 264 will be increased as springs 275 are further compressed. This increased pressure produces sufficient friction between said buttons and said surface to effect the rotation of index plate 249 with gear 261.

Before it is possible for this indexing rotation of index plate 249 to take place, however, index finger 244 must be removed from the serration of said index plate in which it is currently disposed. This disengaging action is accomplished by the combined action of a cam 280, anchored to rotate with gear 261, and cam follower 281, depending from push pin 241.

Such cam follower depends from push pin 241 by means of pivot pin 282 and is continuously caused to contact the surface of cam 280 due to the action of compression spring 283 disposed at the opposite extremity of push pin 241. It will be observed that as rack 260 reciprocates in-

wardly, gear 261 will rotate cam 280 to move follower 281 and push pin 241; simultaneously effecting further compression of spring 283 and removing index finger 244 from its locking position in a serration of said index plate.

The index finger is held in such disengaged position only for a time sufficient to allow index plate 249 to begin the indexing rotation. At that instant, cam follower 281 passes over the crest of cam 280 and compression spring 283, acting on push pin 241, forces index finger 244 into contact with the peripheral edge of index plate 249. This permits said index finger to follow said peripheral edge to the immediately succeeding serration in said periphery, into which said index finger is forcibly disposed by the action of such compression spring, thereby locking the index plate against further rotative movement.

It will be quite obvious that the number of serrations on index plate 249 must be equal to the number of interdental spaces between the teeth of the workpiece. This has been provided for by making said index plate removable when necessary. It is quite obviously seen that the index plate may quickly be changed by removing nut 250, after which said plate may be removed and replaced with another having the desired number of serrations.

After this indexing reciprocation of rack 260, limit switch 284 effects the return of rack 260 to initial position. At the termination of the inward reciprocation, rack 260 contacts arm 285 of said limit switch. This again energizes solenoid valve 255, causing said valve to reverse the flow of pressurized fluid from chamber 256 of cylinder 257 into chamber 286 thereof, reversing thereby the direction of reciprocation of the rack.

Reciprocation of rack 260 in this outward direction rotates gear 261 only, inasmuch as index plate 249 is locked by index finger 244. In providing for such rotation, cam follower 281 was constructed to pivot about pivot pin 282, to prevent lifting of the index finger during this reverse rotation of said gear. It is to be noted that surface 287 of said follower is a portion of a circle and, as cam 280 is reversibly rotated, permits the follower to pivot as the cam moves. In contrast, surface 288 thereof is flat to bear against the adjacent flat surface of push pin 241, preventing said follower from pivoting during indexing rotation of the cam. When cam 280 returns to its initial position, tension spring 289, secured to eye 290 of said follower and to disc 228 by pin 291, forcibly pulls the follower into position for the next indexing action.

Reciprocation of rack 260 in this return direction also relieves the pressure between friction buttons 267 and surface 264 of index plate 249. It will be seen that as rack 260 reciprocates to an initial position, the head of bolt 269 will again contact said rack at its thin extremity and shifter 263, due to its eccentricity with respect to pin 270, will oscillate to its initial position. This eliminates the pressure between contact pins 265 and surface 266 of gear 261 which in turn relieves the pressure between said friction pins and the index plate surface.

As the teeth of the workpiece are in this manner presented to the grinding wheel, a second counting means (not shown) is provided to count the inward reciprocations of rack 260. This counter is adjustable to the number of teeth on the workpiece and is also activated by limit switch 284 as rack 260 contacts arm 285 thereof.

Inasmuch as rack 260 makes one such reciprocation for each tooth, this affords a simple means to insure that all teeth are presented to the workpiece.

After all teeth of the workpiece have been presented to the grinding wheel in this described manner, it is at times desirable to remove an extremely small amount of stock. Provision is made to rotate previously described gear 267 to accomplish a fine adjustment of the workpiece for such operation.

Before this fine adjustment may be made, it is necessary to unlock gear 267 from disc 228. This is effected by loosening bolt 292 which passes through arcuate opening 293 in said gear to threadably engage a tapped opening in disc 228. Such bolt is provided with a conveniently accessible handle 294 by which it may be turned to loosen said bolt and free gear 267 for independent rotation. It will be apparent that gear 267 must be locked again after the adjustment is made in order that rotation of disc 228 be imparted to said gear and thence to index finger 244.

In order to accomplish this adjustment, a manually rotatable shaft 295, having worm 296 formed thereon, is journaled for rotation in an opening 297 provided by disc 228 by means of bearings 298, 299. As such shaft is rotated by means of knob 300 integrally attached thereto, worm 296 drives worm gear 301 and shaft 302 for driving worm 303 formed on said shaft. Such shaft 302 is rotatable normal to shaft 295 and is disposed within an opening 304 of disc 228. Said shaft provides bearing surfaces 305, 306 to bear against the wall of opening 304 and also provides an annular groove 307 to receive pin 308 which is secured to disc 228 to prevent the lower face of worm 303 binding on the bottom surface of opening 304. Thus, as worm 303 is rotated, worm gear 40 267 rotates, effecting index finger 244 to press upon the side of the serration of index plate 249 in which said index finger is currently disposed. This causes index plate 249 to rotate workpiece 78 toward the grinding wheel in readiness for 45 grinding.

As a means for controlling this fine adjustment, a graduated index wheel 309 is secured to shaft 265. This enables the operator to control the necessary adjustment with extreme accuracy as 50 he moves the wheel past the indicator mark at 310.

It is pointed out that this adjustment is limited to the length of arcuate opening 293 in gear 267 which is only one and one-half times the diameter of bolt 262. Such adjustment is intended to augment the previously described adjustments when an extremely small amount of stock is to be removed from a flank of a tooth.

Up to this point nothing has been said about a means for driving this grinding machine. In order 60 to drive a grinding machine of my invention, driving means are provided interiorly of base 1. A suitable prime mover in the form of an electric motor 93 is provided to drive double pump 311. Electric current may be supplied to said motor 65 from a convenient source, the supply being controlled by start button 91 and stop button 92.

Such pump 311 supplies fluid under pressure through line 312 to port 313 or four-way valve 314. Said valve, in this system, has two ports plugged 70 and is used to close the circuit or permit all the fluid to pass through port 315 and line 316 for return to reservoir 317 which stops the machine without stopping motor 93. This is a solenoid valve which may be operated manually to initiate 75 operation of the grinding machine, and operated

by means of the solenoid to automatically stop the same after the grinding operation is completed.

To effect the closing of port 315 in valve 314, control lever 318 (Figure 1) is manually moved. Pressurized fluid then travels through line 319 to port 320 of solenoid valve 255; through line 321 to port 322 of four-way valve 212; and through line 323 to port 324 of sequence valve 325.

Such valve 212 is controlled by means of pilot 207. In this system, one port of said valve is 10 plugged, and depending upon the direction of reciprocation of cylinder 193, port 326 is alternately open to pressure port 322 or reservoir port 327.

The automatic reciprocation of cylinder 193 is accomplished by pilot valve 207 as previously described in connection with reciprocating table 86. Fluid under pressure is delivered by line 328 to port 329 of this valve. In Figure 7, said pilot valve is shown with port 330 and line 331 open to port 329 with port 332 closed. This effects valve 212 to open port 326 to port 322 and closes said port 326 to port 327, permitting delivery of fluid under pressure to line 333 and passageway 334 into chamber 203 of cylinder 193, reciprocating said cylinder downwardly. Simultaneously pressurized fluid from chamber 204 is exhausted by way of passageway 335 and line 336 to port 337 of valve 325 for return therethrough to the system.

This is known as a differential system and cylinder 193 is termed a differential cylinder. In order for such system to function, the ratio of surface areas of piston 205 must be 2 to 1. In this invention, the lower surface 338 of said piston has twice the area of upper surface 339 to piston rod 199 being sufficiently large to make this ratio possible. It will be evident that such system permits cylinder 193 to reciprocate with equal speed in either direction.

When pilot valve 207 is shifted to an alternate position by dog 209, port 332 and line 340 are open to port 329 and port 330 is closed thereto. This effects valve 212 to open port 326 to port 327 and close said port 326 to port 322. In this condition, fluid under pressure flows through line 323 valve 325, line 336 and passageway 335 into chamber 204, reciprocating cylinder 193 in an upward direction. At the same time, fluid in chamber 203 is exhausted by retracing the path to port 326 for delivery to port 327 and to reservoir 317 by way of lines 341, 342, 316.

In connection with the description of the indexing mechanism, it was explained that the indexing reciprocation of rack 260 took place after a predetermined number of reciprocations of cylinder 193. For this indexing reciprocation, solenoid valve 255 opens port 320 to port 343 and line 344 to chamber 256. Simultaneously, port 345 is closed to port 320 and opened to port 346 to allow fluid in chamber 286 of said cylinder 257 to exhaust through line 347 for return by way of said ports 345, 346, and lines 342, 316 to reservoir 317. Reciprocation in an opposite direction to return rack 260 to an initial position is accomplished when this circuit is reversed as limit switch 284 actuates solenoid valve 255 to open port 345 and line 347 to chamber 286. At this time, port 343 is closed to port 320 and open to port 346 to permit fluid in chamber 256 to exhaust to reservoir 317.

It is during the indexing reciprocation of rack 260 that sequence valve 325 functions to prevent reciprocation of cylinder 193 and thus table 86. Such valve 325 is remotely controlled and such control is effected when port 320 is open to port

343 and line 344. At that instant, pressurized fluid is delivered by line 348 to valve 325, effecting thereby the closing of port 324 and stopping the flow of pressurized fluid in either direction with respect to chamber 204 of piston 193, thereby preventing reciprocation of said cylinder.

Provision is made in this fluid system for controlling the speed of reciprocation of cylinder 193 at all times by means of a flow control valve 349. Lever 350 on this valve may be used to set said valve to permit a definite pressure to build up in the system. When this pressure is reached, port 351 of said valve is opened to port 352, and fluid under pressure is returned through lines 353, 354, 316, to reservoir 317.

Upon completion of the grinding operation, a grinding machine of my invention is automatically stopped. It was previously disclosed that a counting device counted the number of indexing reciprocations made by rack 260. When all teeth 20 of the workpiece have been indexed, this counting device closes an electric circuit energizing control solenoid valve 314. Such valve then opens port 313 to port 315 and the fluid under pressure from line 312 is delivered by line 354 to be returned to reservoir 317 by way of said valve and line 316, stopping the grinding operation until control lever 318 is used to again close port 313 to port 315.

It will be apparent from the foregoing description that the grinding machine of my invention as described and shown in the accompanying drawings has been described and illustrated in specific detail. It will be readily obvious that many modifications, changes, or departures therefrom may be made without departing from the generic spirit and scope of the invention as set forth in the claims hereinafter set forth.

What is claimed is:

1. A grinding machine for grinding the flanks of the teeth of gear-like machine elements comprising a base, a table mounted upon said base, means for moving said table in a rectilinear and substantially horizontal path upon said base, means for swinging said table about a substantially vertical axis with respect to the base, work holding means carried by said table including centering means defining an axis for rotatable support of a workpiece, which axis is generally parallel to the aforementioned rectilinear path, a grinding head independently supported by said base in a position above said centering means, means carried by said head for supporting a generally circular grinding wheel having a straight surface normal to its axis of rotation in a position wherein the wheel may overhang and contact a workpiece carried by said work holding means, and means for imparting lateral reciprocation to the work holding means in a path perpendicular to the aforementioned axis while simultaneously imparting oscillatory partial rotation to the centering means about such axis at a rate adapted to maintain rolling engagement between the aforementioned surface of the wheel and the flank of a tooth carried by a workpiece, including a work-oscillating motor entirely carried by and adapted to travel with said work holding means and reacting against a fixed portion of the base to impart such transverse reciprocation to the work holding means, the means whereby the motor reacts against the base including an adjustable cam-type reaction element carried by the base whereby the length of the path of reciprocating movement may be varied at will, and means responsive to such reciprocating move-

ment for imparting oscillatory partial rotation to the centering means, whereby by adjustment of said first-mentioned cam-type reaction member the length of the rectilinear reciprocatory movement and the extent of angular partial rotation may be simultaneously varied.

2. Means as set forth in claim 1 in which said means for imparting oscillatory rotation to the centering means includes adjustable reaction bands providing independent driving connection between the base and said work holding means.

3. Means as set forth in claim 1 in which said means for imparting oscillatory rotation to the centering means includes adjustable reaction bands providing independent driving connection between the base and said work holding means, and means for rotating the centering means independently of the bands for indexing, including a separate motor carried by the work holding means.

4. In combination with means as set forth in claim 1, means including an actuating element carried by the base for reciprocating said table along said first-mentioned rectilinear path simultaneously with said oscillatory and reciprocating movement to feed such a workpiece longitudinally in a path parallel to the aforementioned surface of the wheel.

5. A grinding machine for grinding the flanks of the teeth of gear-like machine elements comprising a base, a grinding head mounted thereon, said head including a generally circular grinding wheel having a flat surface normal to its axis of rotation and means for driving same, a work holder mounted on said base, said work holder including centering means and a work supporting element for rotatably supporting a workpiece, automatic fluid actuated means for reciprocating said work holder to move a workpiece mounted therein in a path normal to its axis of rotation, means to effect reciprocatory partial rotation of said work supporting element in accordance with said reciprocating movement, including a driving element carried by said base and a coacting driving element carried by the work holder, the combined rotational and reciprocating movements serving to cause the flank of a tooth of the workpiece to progressively contact the surface of the grinding wheel along an involute path, common means for precisely limiting the magnitude of both of said reciprocatory movements, and means

including a vertical pivot operatively connecting the work holder to the base for swinging movement about a vertical axis.

6. A grinding machine for grinding the flanks of the teeth of gear-like machine elements comprising a base, a grinding head mounted thereon, said head including a generally circular grinding wheel having a flat surface normal to its axis of rotation and means for driving same, a work holder mounted on said base, said work holder including centering means and a work supporting element for rotatably supporting a workpiece, automatic fluid actuated means for reciprocating said work holder to move a workpiece mounted therein in a path normal to its axis of rotation, means to effect reciprocatory partial rotation of said work supporting element in accordance with said reciprocating movement, including a driving element carried by said base and a coacting driving element carried by the work holder, the combined rotational and reciprocating movements serving to cause the flank of a tooth of the workpiece to progressively contact the surface of the grinding wheel along an involute path, common means for precisely limiting the magnitude of both of said reciprocatory movements, means including a pair of tables, one supported by the other and both carried by the base, said tables being movable at right angles to one another upon the base and said work holder being carried by said tables, and means including a vertical pivot also operatively connecting the work holder to the base for swinging movement about a vertical axis.
